UNITED STATES PATENT OFFICE.

CAROLINE WALLE, OF BERLIN, NORTH DAKOTA.

WATER-HEATER.

1,283,379.

Specification of Letters Patent. Patented Oct. 29, 1918.

Application filed June 13, 1917. Serial No. 174,563.

To all whom it may concern:

Be it known that I, CAROLINE WALLE, residing at Berlin, in the county of La Moure and State of North Dakota, have invented 5 certain new and useful Improvements in Water-Heaters, of which the following is a specification.

This invention relates to water heaters and more particularly to heaters adapted 10 particularly for bath use. The heater comprises a tank to contain water and a cover for the tank which may be removed from the top of the tank and disposed upon the floor to form a bath tub. The invention 15 consists in the combination and arrangement of parts to be hereinafter fully described in the following specification, pointed out in the appended claims and illustrated in the accompanying drawing which forms a part 20 of the specification and in which—

Figure 1 is a side elevation of my improved water heater, the cover being shown in its position for use as a bath tub in dotted lines.

25 Fig. 2 is a top plan view of Fig. 1.

Like reference characters denote corresponding parts in both views.

The reference numeral 1 denotes a water tank supported upon legs 2 which legs also 30 carry a shelf 3 whereon a gas stove 4 fed by gas supply pipe 5 is carried. The water tank 1 is provided with the inlet pipe 6 and with the flexible outlet pipe 7 provided with stop cock 7^a. The said water tank, 35 further, is provided along one end with the vertically disposed flanges 8, 8 which extend below the base of said tank and which are slotted longitudinally at 9 to receive the sliding bolts 10 carried by the angular 40 guide arms 11 which are carried by the cover 12 which is provided with the handle 13. In Fig. 1 of the drawing the cover 12 is shown upon the tank 1. In this position the water, previously introduced into the 45 tank through the pipe 6, is heating. To remove the cover 12 the operator grasps the

handle 13 and raises the cover and moves it into the position shown in dotted lines. This operation moves the arms 11 longitudinally of the flanges 8 and moves the bolts 10 through the slots 9. The cover is placed upon the floor in inverted position with respect to the position shown in full lines on top of the tank 1. The flexible pipe 7 is now used to conduct water from the tank 55 into the cover which may then be used as a bath tub after which it may be emptied by removing the bolts 10 and emptying the water in any manner desired. The cover can then be again connected to the tank and 60 is ready for the next operation.

What is claimed is:—

1. In a water heater, a tank having an inlet and an outlet pipe, flanges formed upon said tank and a cover movably connected to 65 said flanges and adapted to fit said tank as a closure therefor and to be removed from said tank and disposed beside the same to serve as a receptacle for the contents of said tank which are conducted thereinto through 70 the medium of said outlet pipe.

2. In a water heater, a water tank, longitudinally slotted flanges formed upon said tank, a cover adapted in one position for disposal upon said tank to form a closure therefor, guide arms for said cover slidably over the said flanges, bolts carried by said guide arms slidably disposed in the slotted portions of said flanges through the medium of which and said guide arms said cover may be 80 moved from said tank and disposed beside the same and an outlet pipe for said tank adapted to lead into said cover in its non-operative position as a closure for said tank. 75

In testimony that I claim the foregoing 85 as my own I have hereto affixed my signature in the presence of two subscribing witnesses.

CAROLINE WALLE.

Witnesses:

J. E. LAINGEN,
J. M. LEPPERT.
